UNITED STATES PATENT OFFICE

VICTOR S. THARP, OF ELMHURST, ILLINOIS, ASSIGNOR TO AUTOMATIC ELECTRIC INC.,
OF CHICAGO, ILLINOIS, A CORPORATION OF DELAWARE

TELEPHONE SYSTEM

Application filed September 22, 1926. Serial No. 136,925.

This invention pertains to automatic telephone systems in general, but is more particularly concerned with telephone systems in which calls to dead or temporarily-interrupted-service numbers are automatically extended to an intercepting operator. The object of the invention is the provision of a new and improved trunk circuit for the trunk over which calls to dead or temporarily-interrupted-service numbers are automatically trunked to an intercepting operator without causing the registration of the call on the calling subscriber's meter.

In the ordinary course of events in the extension of a call from a calling to a called subscriber, one or more switches are operated, the last switch being a connector, for example a Strowger vertical and rotary type connector, and when the called subscriber answers the call, a bridge is placed across the called line which causes the operation of a ring-cut-off relay in the connector to cut off the ring and complete the connection, and also causes the operation of a back-bridge relay, the latter relay functioning to reverse the normal current flow over the calling line to operate the calling subscriber's meter. When a call is trunked to an intercepting operator and the call is answered by the intercepting operator, means must be provided to operate the ring-cut-off relay in the connector switch to cut off the ring and complete the talking connection, yet prevent the operation of the back-bridge relay in order to prevent the registration of the call on the calling subscriber's meter, since it is ordinarily not desired to charge a subscriber for an intercepted call.

The object of the invention and the new features accomplished will be described in detail in the following specification with the aid of the annexed drawing, which shows by means of the usual schematic circuit diagrams the new and improved intercepting trunk circuit together with sufficient of the associated apparatus to enable the invention to be clearly explained and its utility appreciated.

Referring to the drawing, the frequency selecting connector FS is one of a group of

frequency selecting connectors for extending connections to party lines, such as the party line comprising conductors 21 and 22. The connector FS is of the well known Strowger vertical and rotary type like that shown and described in detail in the Patent No. 1,606,446, granted to Arthur J. Ray, November 9, 1926. In the drawing only those elements of the connector FS are shown that are particularly concerned with the present invention.

The connector C is one of a group of individual line connectors for extending connections to individual lines, such as the line comprising conductors 21' and 22'. This connector is also of the well known Strowger vertical and rotary type like that shown and described in detail in Patent No. 1,580,490 granted to Emil Jacobsen April 18, 1926. Only those elements which are particularly concerned with this invention are shown in the drawing.

At the distributing frame DF, the terminals 17 and 18, connected to connector bank contacts 15 and 16, respectively, and the terminals 19 and 20, terminating the party line comprising conductors 21 and 22, are cross connected by means of jumpers 23 and 24. A connection may thus be established with any one of the parties on the party line, comprising conductors 21 and 22, by operating a frequency selecting connector, such as connector FS, to connect with bank contacts 15 and 16, or contacts multiply connected therewith. Similarly, at the distributing frame DF, terminals 17' and 18' connected to bank contacts 15' and 16' respectively, and terminals 19' and 20' terminating the individual line comprising conductors 21' and 22', are normally cross connected by means of jumpers, so that connections with this line ordinarily may be established by operating a connector, such as connector C, to engage the bank contacts 15' and 16', or contacts multiply connected therewith.

The subscribers' substations A'-A¹⁰, inclusive, A⁶ being shown in full, and the others being indicated by showing the bells only, are of the usual automatic type, having their ringers connected from either one or the

other side of the line to ground. The substation A¹¹ is identical to the substation A³ except that its ringer is bridged directly across the line.

5 The reference character O indicates an intercepting operator's cord circuit. Since this forms no particular part of the invention, only the sleeve relay connections and the sections of the talking conductors terminating in the plug P are shown.

10 Terminating in the jack J is the intercepting trunk comprising conductors 71—74, inclusive. Associated with this trunk is the trunk relay group TC, the circuit arrangements of which form a particular part of 15 this invention and will be described in detail hereinafter.

15 Multiply connected to this intercepting trunk are traffic ringers, such as traffic ringers TR' and TR. Each traffic ringer comprises a frequency relay which responds only 20 to a particular frequency of ringing current, and a switching relay with connections as shown.

25 Under ordinary conditions when service is being extended to all ten substations on the party line comprising conductors 21 and 22, no connection is made from this line to a traffic ringer. In the present case, however, 30 it is assumed that service to one of the substations on this line, substation A³, is temporarily interrupted, and that the conductors leading to sub-station A³ from the party line conductors 21 and 22 have been disconnected. 35 For this reason, at the distributing frame DF, the terminals 27 and 28 connected to the traffic ringer TR, are cross-connected to terminals 17 and 18 by means of jumpers 25 and 26, assuming that the frequency re-

40 lay 32 of traffic ringer TR is connected to the same side of the line to which the ringer at substation A³ is ordinarily connected and responds to the same frequency of ringing current. Now calls to substation A³ will au-

45 tomatically be extended to an intercepting operator as will be described in detail hereinafter. Under ordinary conditions when service is extended to substation A¹¹, jumpers connecting terminal 17' with terminal 19', and terminal 18' with terminal 20' are supplied. It is assumed in this case, however, 50 that service to the substation A¹¹ is temporarily interrupted, and that, as shown, terminals 17' and 18' are connected to terminals 27' and 28', respectively, assuming that frequency relay 32', connected across the line, 55 responds to the same frequency of ringing current as the ringer at substation A¹¹. Again, as in the above case, calls attempted with substation A¹¹ will automatically be trunked to the intercepting operator as will be described hereinafter.

With this general description of the object of the invention and of the apparatus shown in the drawing in mind, a detail description

of the operation of the apparatus will now be given. For this purpose it will first be assumed that some subscriber either inadvertently dials the number of the substation A³, or dials this number to obtain connection therewith not knowing that service thereto is temporarily interrupted. Responsive to the digits dialled by the calling subscriber, automatic switches are operated, each switch extending the connection to a succeeding switch, the final switch operated being a frequency selecting connector, which in this case will be assumed is the frequency selecting connector FS. This switch operates responsive to the first two of the last three digits of the called number to position its wipers 13 and 14 in engagement with bank contacts 15 and 16 connected to the party line comprising conductors 21 and 22, and operates responsive to the last digit dialed to position the frequency selecting wipers 5 and 6 in engagement with the contacts 11 and 12 respectively, thereby selecting the frequency of ringing current and the side of the line to which it is to be applied, which would ordinarily operate the ringer at substation A³.

At the completion of the dialling of the number, operations take place in the frequency selecting connector FS (described in detail in the above referred to reference concerning the operations of this connector) at the completion of which a circuit may be traced from the battery superimposed generator G or direct battery, bank contact 11, wiper 5, resting contact and armature 9, wiper 13, bank contact 15, terminal 17, and then over two paths, one path including jumper 23, terminal 19, party line conductor 21, through the ringers connected to this side of the line to ground, the other path including jumper 25, terminal 27, through the winding of frequency relay 32 to ground. As has been stated, the substation A³ is disconnected from the party line; and the other ringers connected to conductor 21 are tuned so as not to respond to the frequency of ringing current supplied by generator G, the particular generator now being used. As frequency relay 32, however, is tuned to respond to ringing current from the generator G, this relay operates. As soon as armature 36 engages its working contact, a circuit is established which may be traced from ground by way of armature 57 and the resting contact, armature 60 and the resting contact, conductor 72, armature 36 and the working contact, through the upper winding of switching relay 31 to battery. Relay 31 operates and closes a locking circuit for itself at armature 34 which may be traced from ground by way of the normally closed contacts controlled by armature 59, resting contact and armature 67, through the winding of impulse control relay 52, conductor 73, armature 34 and the working contact, through the lower winding of

relay 31 to battery. By the actuation of armatures 33 and 35, the connection is extended to the intercepting trunk comprising conductors 71—74, inclusive. Relay 52 energizes over the above traced circuit and by the disengagement of armature 60 from its resting contact, ground potential is removed from conductor 72 to prevent another connection from being extended to this particular intercepting trunk at this time, and by the engagement of armature 60 with its working contact, a circuit is closed for the impulse relay 54. Relay 54 operates and prepares the impulse circuit at armature 64, and at armature 65 closes the circuit for the bridge control relay 53. Relay 53 operates and closes another point in the impulse circuit at armature 62, closes the circuit for the call lamp L at armature 61, and at armature 63 opens a point in the circuit of switching relay 55.

The lighting of the lamp L indicates to the intercepting operator that a call has been extended over the trunk terminating in the jack J, in response to which she inserts the plug of an idle cord, plug P of the cord O, for example, into the jack J. Inserting the plug P into the jack J closes the circuit for the sleeve relay 51 in series with the sleeve relay of the cord O. Relay 51 operates and at armature 59 excludes relay 52 from the holding circuit of relay 31 of the traffic ringer TR; at armature 58 prepares the circuit for the switching relay 55; and by the disengagement of armature 57 from its resting contact opens the circuit of relay 54 and of the call lamp L, and by the engagement of this armature with its working contact places ground potential by way of working contact and armature 64, working contact and armature 62, to the midpoint of the bridge across the conductors 74 and 71 which includes the windings of impedance 56 and the resistances R and R'. The application of ground potential to the midpoint of this bridge has no utility in this particular connection.

Shortly after the interruption of its circuit, relay 54 deenergizes and at armature 65 opens a circuit of relay 53, and by the release of armature 64 ground potential from the midpoint of the bridge including the resistances R and R' and the windings of impedance 56 is removed, and battery potential through the protective resistance R² is substituted therefor. A circuit may now be traced from battery, resistance R², resting contact and armature 64, working contact and armature 62, resistance R, lower winding of impedance 56, conductor 74, armature 35 and the working contact, jumper 26, bank contact 16, wiper 14, resting contact and armature 10, wiper 6, bank contact 12, through the lower winding of the ring cut-off relay 4 to ground. The ring cut-off relay 4 operates over this circuit and at armatures

9 and 10 disconnects the ringing circuit and bridges the windings of the back-bridge relay 2 across the talking conductors. The relay 2 is prevented from operating by reason of the following: After the operation of relay 4, the upper winding of relay 2 is short circuited by reason of battery potential being connected to the midpoint of the bridge across conductors 71 and 74, and relay 2 is insufficiently energized over its lower winding by reason of the resistance R to effect its operation. Shortly after its circuit is opened, relay 53 releases its armatures, closing the circuit for switching relay 55 at armature 63 and disconnecting battery potential from the midpoint of the bridge across conductors 71 and 74 at armature 62. The short circuit is now removed from the upper winding of the back-bridge relay 2, but the closed circuit now including both windings of the back-bridge relay 2 and both windings of the impedance 56 and resistances R and R', has practically twice the resistance as the previous circuit which included only the lower winding of back-bridge relay 2, and resistance R and the lower winding of impedance 56. Therefore the magneto motive force produced by current in both the windings of the back-bridge relay is not materially changed and the relay remains de-actuated. Consequently, since the back-bridge relay 2 is not operated, the normal current flow over the calling line supplied through the windings of the line relay 3 is not reversed and the subscriber's meter (not shown) is not operated.

Shortly after its circuit is closed, switching relay 55 operates and at armatures 66 and 68 completes the talking connection from the calling subscriber to the intercepting operator who, after connecting her head set (not shown) across the talking conductors of the cord in known manner, informs the calling subscriber that service to the substation A³ is temporarily interrupted or gives other information as she may have to give the calling subscriber concerning the subscriber at substation A³. The calling subscriber will then replace his receiver, initiating the release of the operated switches in the well known manner, and the intercepting operator will remove the plug P from the jack J.

Removing the plug P from the jack J opens the circuit of the sleeve relay 51 which deenergizes and releases its armatures. By the release of armature 59, the circuit of switching relay 31 of the traffic ringer TR is opened, which thereupon deenergizes and restores its armatures to normal. By the release of armature 58, the circuit of relay 55 is opened. Relay 55 retains its armatures operated for an interval to allow for the release of relay 31 so that the holding circuit of relay 31 is not restored by the release of

armature 67. After the lapse of the interval, relay 55 restores its armatures to normal.

It is obvious from the foregoing descriptions that if service to any other of the parties 5 on the party line comprising conductors 21 and 22 also be temporarily interrupted, another set of jumpers similar to jumpers 25 and 26 would be connected from terminals 17 and 18 to the terminals of another traffic 10 ringer, whose frequency relay was tuned to respond to the same frequency of ringing current as the ringer at that substation, and was connected to the same side of the line. The dialling of the number of that substation 15 by some calling subscriber would again result in the establishment of a connection to the intercepting operator.

It is also evident that it is immaterial to what side of the line the cut-off winding of 20 the ring cut-off relay 4 is connected (being connected to the lower conductor via wiper 6 when a substation whose ringer is connected to one conductor of a party line is to be signalled, and to the upper conductor via wiper 25 5 when a subscriber whose ringer is connected to the other conductor of the party line is to be signalled), the operation being the same in either case. In one case the circuit for energizing the cut-off winding extends 30 from the midpoint of the bridge across the conductors 71 and 74 over resistance R, the lower winding of the impedance 56, and in the other case, over resistance R' and the upper winding of the impedance 56 and conductor 71.

It will be recalled that included in the operations performed in the above connection, a ground potential was momentarily applied to the midpoint of the bridge across conductors 71 and 74, which operation had no function in the setting up of that connection. To describe the utility of this operation in the 40 trunk circuit TC, it will be assumed that a calling subscriber either inadvertently dials the number of the substation A¹¹, or dials the number of the subscriber at substation A¹¹ not knowing that service thereto has been temporarily interrupted. Responsive to the dialling of the digits of this number, a connection 45 is established from the calling subscriber by way of one or more automatic switches, the last of these switches, it will be assumed, is the connector C which operates responsive to the dialling of the last two digits of the 50 number to position its wipers 13' and 14' in engagement with the bank contacts 15' and 16'. These bank contacts, though normally cross-connected to the line conductors 21' and 22', are now cross-connected to the traffic 55 ringer TR'. At the end of the dialling period, the connector functions to project ringing current over the two sides of the line in series across which the frequency relay is now bridged. Frequency relay 32' operates 60 responsive thereto, closing an initial energiz-

ing circuit for relay 31' which in turn operates and initiates relay operations in the trunk circuit TC that effect the lighting of lamp L. When the operator answers the call by inserting the plug of a cord, plug P for example, into the jack J, relay 51 operates and at armature 57 places ground potential on the junction point of resistances R and R' via armatures 64 and 62. Since the operating winding of the ring cut-off relay 4' is connected to battery, this relay immediately operates over a circuit similar to that over which the relay 4 in the previously described connection operated. Relay 4' in operating, cuts off the ring and bridges the back-bridge relay 2' across 75 the talking conductors. The back-bridge relay 2' does not operate, however, since its lower winding is now short circuited by reason of the ground potential at the midpoint of the bridge across the conductors 71 and 74. 80 Relay 51 in operating also opens the circuit of relay 54. A short time after its circuit is opened, relay 54 releases its armatures and as previously described connects battery to the midpoint of the bridge across the conductors 71 and 74. Back-bridge relay 2' does not operate because now its upper winding is short circuited. Relay 54, in releasing its armature 65, also opens the circuit of relay 53. A short time after its circuit is opened, 85 relay 53 deenergizes and disconnects battery potential from the midpoint of the bridge across conductors 71 and 74. As previously described, the back-bridge relay 2' is not energized in series with both resistances R and R' and both windings of the impedance 56 sufficiently to operate. Again, since relay 2' is prevented from operating, the normal current flow supplied to the calling line through the windings of the line relay 3' is not reversed, and consequently the calling subscriber's meter is not operated.

From the foregoing description, it is seen that a trunk circuit for an intercepting trunk is provided which contains means for operating the ring cut-off relay in the connector switch irrespective of the side of the line to which its operating winding may be connected, or to what pole of the battery this winding may be connected, and prevents the 100 operation of the back-bridge relay of the connector used so that the subscriber's meter will not be operated.

The invention, its operation and utility, having been described, what is considered new and is desired to have protected by Letters Patent is specifically stated in the appended claims.

What is claimed is:

1. In a telephone system, an operator's position, a trunk line, means including a connector switch for extending a connection to said position, a ring cut-off relay in said switch, a back-bridge relay in said switch normally responsive to the operation of said 115

- ring cut-off relay, means responsive when the call is answered for operating said ring cut-off relay and for shunting one winding of said back-bridge relay to prevent said back-bridge relay from operating. 5
2. In a telephone system, an operator's position, a trunk line, means including a switch for extending a connection to said position, a ring cut-off relay in said switch, a back-bridge relay in said switch normally responsive to the operation of said ring cut-off relay, a bridge comprising two resistances connected in series across said trunk line, and means operative when the call is answered for connecting a characteristic potential to the junction of said resistances to operate said ring cut-off relay and for shunting one winding of said back-bridge relay to prevent the operation of said back-bridge relay. 10
- 15 3. In a telephone system, an operator's position, a trunk line, means including a connector switch for extending a connection to said position, a ring cut-off relay in said switch adapted to be connected to either side of said trunk line, a bridge comprising two resistances connected in series across said trunk line, and means responsive to the answering of the call for connecting a characteristic potential to the junction of said resistances to operate said ring cut-off relay irrespective of the side of said trunk line to which said ring cut-off relay is connected. 20
- 25 4. In a telephone system, a battery, a switch, a ring cut-off relay in said switch connected to one pole of said battery, a second switch, a ring cut-off relay in said second switch connected to the other pole of said battery, an operator's position, a trunk line, means for extending a connection to said position via said trunk line and either of said switches, and means responsive to the answering of the call for successively connecting the poles of said battery to said trunk line to operate the ring cut-off relay in the switch used. 30
- 35 5. In a telephone system, a battery, a switch, a ring cut-off relay in said switch connected to one pole of said battery, a second switch, a ring cut-off relay in said second switch connected to the other pole of said battery, an operator's position, a trunk line, means for extending a connection to said position via said trunk line and either of said switches, a bridge across said trunk line, and means responsive to the answering of the call for successively connecting the poles of said battery to the midpoint of said bridge to operate the ring cut-off relay in the switch used. 45
- 40 6. In a telephone system, a battery, a switch having two wipers, a ring cut-off relay in said switch connected to one pole of said battery and adapted to be connected to either of said wipers, a second switch, a ring cut-off relay in said second switch connected to the other pole of said battery, an operator's 45
- position, a trunk line, means for extending a connection to said position via said trunk line and either of said switches, a bridge across said trunk line, and means responsive to the midpoint of said bridge to operate the ring cut-off relay in the switch used. 50
- 55 7. In a telephone system, an operator's position, a signal at said position, a trunk line, a battery, a first switch, a second switch, a ring cut-off relay in said first switch connected to one pole of said battery, a ring cut-off relay in said second switch connected to the other pole of said battery, means for extending a connection to said position including either of said switches via said trunk, a first relay and a second relay, means responsive to the completion of said connection for successively operating said first and second relays, means controlled by said second relay for operating said signal, means operative when the call is answered for successively deactuating said first relay and said second relay to momentarily and successively connect the poles of said battery to said trunk line to operate the ring cut-off relay in the switch used. 55
- 60 8. In a telephone system, a trunk line and means for extending a call thereover, means for answering the call, a battery and means automatically responsive when the call is answered for momentarily and successively connecting the two poles of said battery to said trunk line. 65
- 65 9. In a telephone system, a trunk line and means for extending a call thereover, means for answering the call, a bridge including two serially connected resistances across the conductors of said trunk, and means automatically responsive when the call is answered for momentarily and successively applying potentials to the junction of said resistances. 70
- 70 10. In a telephone system, a trunk line and means for extending a call thereover, means for answering the call, a battery and means automatically responsive when the call is answered for momentarily and successively connecting the poles of said battery to both conductors of said trunk line. 75
- 75 11. In a telephone system, a trunk line and means for extending a call thereover, means for answering the call, two slow-acting relays and means for operating them, and means responsive when the call is answered for successively deactuating said relays to momentarily and successively applying potentials to said trunk line. 80
- 80 12. In a telephone system, a trunk line and means for extending a call thereover, means for answering the call, a bridge including two serially connected resistances across the conductors of said trunk line, a 85
- 85

battery, and means responsive when the call is answered for momentarily and successively connecting the two poles of said battery to the junction of said resistances.

13. In a telephone system, a trunk line and means for extending a call thereover, means for answering the call, a battery, two relays and means for operating them, and means responsive when the call is answered for successively deactuating said relays to momentarily and successively connect the two poles of said battery to said trunk line.

14. In a telephone system, a trunk line and means for extending a call thereover, means for answering the call, a bridge including two serially connected resistances across the conductors of said trunk line, a battery, two slow-acting relays and means for operating them, and means responsive when the call is answered for successively deactuating said relays to momentarily and successively connect the poles of said battery to the junction of said resistances.

15. In a telephone system, a trunk line, means including a connector switch for extending a call over said trunk line, means for answering the call, a ring cut-off relay in said connector switch adapted to be connected to either side of said trunk line, and means responsive to the answering of the call for placing a characteristic potential on the conductors of said trunk line to operate said relay irrespective of the side of the trunk line to which said relay is connected.

16. In a telephone system, a trunk line, means including a connector switch for extending a call over said trunk line, means for answering the call, a ring cut-off relay in said connector switch adapted to be connected to either conductor of said trunk line, and means responsive to the answering of the call for operating said relay over the conductor of said trunk line to which said relay is connected independent of the other conductor of said trunk line.

17. In a telephone system, a trunk line, means including a connector switch for extending a call over said trunk line, means for answering the call, a relay in said switch, a second relay in said switch normally responsive to the operation of said first relay, means responsive when the call is answered for operating said first relay over one conductor of the trunk line independent of the other conductor, a resistance, and means responsive to the operation of said first relay over said one conductor of the trunk for inserting said resistance in the circuit of said second relay to prevent the operation of said second relay.

18. In a telephone system, a battery, a switch, a ring cut-off relay in said switch connected to one pole of said battery, a second switch, a ring cut-off relay in said second switch connected to the other pole of said

battery, a trunk line, means including one or the other of said two switches for extending a call over said trunk line, means for answering the call, and means responsive to the answering of the call for completing a circuit over one conductor of said trunk line independent of the other conductor of said trunk line to operate the ring cut-off relay in whichever switch is used.

19. In a telephone system, a battery, a switch having two wipers, a ring cut-off relay in said switch connected to one pole of said battery and adapted to be connected to either of said wipers, a second switch, a ring cut-off relay in said second switch connected to the other pole of said battery, an operator's position, a trunk line, means for extending a connection to said position via said trunk line and either of said switches, and means responsive to the answering of the call for completing a circuit including only one conductor of the trunk to operate the ring cut-off relay of the switch used irrespective of the wiper or of the pole of the battery to which said relay is connected.

20. In a telephone system, a trunk line, means including a connector switch for extending a call over said trunk line, means for answering the call, a back bridge relay in said switch normally responsive to the answering of the call, and means responsive when the call is answered for successively shunting the windings of said relay to prevent the operation of said relay.

In witness whereof I hereunto subscribe my name this 17th day of September, A. D., 1926

VICTOR S. THARP.
